FOLDING AND GLUING MECHANISM

Dietrich Daneke, Topeka, Kans., and Leo C. Williams, Pearl River, N. Y., assignors to The Brackett Stripping Machine Company, Topeka, Kans., a copartnership consisting of Edward M. Brackett and Fred M. Brackett

Application May 18, 1934, Serial No. 726,322

15 Claims. (Cl. 93—1)

This invention relates to a folding and gluing mechanism and has for its principal objects to provide a mechanism of this character for folding and gluing sheet papers, for folding sheet paper over the edge of a card board, and for producing single and double folds in card board folders and similar articles.

In accomplishing these and other objects of the invention, we have provided improved details of structure, the preferred form of which is illustrated in the accompanying drawings, wherein:

Fig. 1 is a perspective view of a folding and gluing machine constructed in accordance with the present invention.

Fig. 2 is a plan view of the machine.

Fig. 3 is a detail perspective view of a portion of the machine illustrating the folding of a paper sheet over the edge of a card board.

Fig. 4 is a cross sectional view on the line 4—4, Fig. 3.

Fig. 5 is a detail plan view of a wiping roller for drawing the folded edge of a sheet tightly over the edge of a card board.

Fig. 6 is a vertical section through a portion of the machine on the line 6—6, Fig. 2.

Fig. 7 is a detail perspective view of one of the forming shoes.

Fig. 8 is a similar view of one of the folding shoes.

Fig. 9 is a sectional view through the folding shoes on the line 9—9, Fig. 12, showing the edge of a paper sheet being folded over the forming shoe.

Fig. 10 is a similar view on the line 10—10, Fig. 12, showing the edge of the paper sheet after it has been moved to forming relation with the forming shoe by the folding shoe.

Fig. 11 is a similar view on the line 11—11, Fig. 12, illustrating the completion of the fold.

Fig. 12 is a plan view of the machine as set up in making a double fold in a card board folder or the like.

Fig. 13 is a cross section through the scoring rollers.

Fig. 14 is a detail sectional view through the forming and folding shoes producing the second fold in a card board sheet.

Fig. 15 is a similar view showing the second fold in further folding condition.

Referring more in detail to the drawings:

1 designates a machine embodying the features of the present invention and which includes a table 2 having a flat substantially rectangular shaped top plate 3 supported at its ends on pairs of vertical legs 4, 5 and 6, 7, the table top being braced to the legs by suitable ties 8 and 9 to form a substantially rigid structure.

Supported at one end of the table is a feeding

shelf 10 that is supported in the plane of the table top by braces 11 connecting the outer end of the shelf with the legs 4 and 5.

The shelf preferably includes a horizontal series of slats 12 extending in the longitudinal direction of the table and adapted to be interarranged relatively to each other whereby a guide strip 13 on one of the slats is adapted to be positioned relatively to a feeding head that is carried by the table 3 later described. Carried at the sides of the shelf are work supporting wings 14 and 15 adapted to support stacks of sheet material which are to be fed through the machine.

The feeding head is designated 16 and includes upper and lower conveyor belts 17 and 18. The lower conveyor belt 18 has its upper run 19 operating in a longitudinal slot 20 extending the length of the table top 2 and supported with its upper face in the plane of the table on a series of rollers 21, the rollers 21 being mounted on pins 22 having their ends supported in longitudinal flanges 23 and 24 depending from the side edges of the slot, as best shown in Fig. 4. The lower run 25 of the upper belt 17 is retained in substantial contact with the upper run of the lower belt by a series of rollers 26 carried by the spaced longitudinal bars 27 and 28 that are suspended over the table by means of goose neck brackets 29 and 30. The rollers 26 are rotatably mounted on shafts 31 having their ends mounted in slots 32 of the longitudinal bars 27 and 28 and are yieldingly urged against the belts by spring pressed plungers 33 and 34 slidably mounted in bores 35 and 36 in the bars and having ends 35 engaging in sockets 37 in the ends of the shafts.

The springs 38 are loosely supported in the bars and have one end engaging the tops of the plungers and their opposite ends engaging plugs 39 threaded in the open upper ends of the bores 40, 35 and 36.

The bars are connected near their ends by U-shaped brackets 40 in which are rotatably mounted vertically positioned screw threaded shafts 41 that are threadedly supported in the horizontal arms 42 of the brackets 29 and 30, the other arms of the brackets being secured to the side of the table by suitable fastening devices. Pressure of the rollers against the belts is regulated to compensate for various thicknesses of sheets passed through the machine by rotating the shafts 41 to raise and lower the side bars, the shafts 41 being operated by hand wheels 43.

Carried by a bar 44 between the brackets 29 and the adjacent ends of the longitudinal bars is 55 a glue pot 45 having a glue applying wheel 46 arranged so that its periphery moves through a slot 47 in the bottom of the glue pot for carrying the glue into contact with the work sheet fed through the machine, as later described. The 60

glue applying wheel is fixed to a shaft 48 having its ends rotatably mounted in depending lugs 49 on the glue pot and in a bearing 50 on a bracket 51 carrying the bar 44.

5 The outer end of the shaft carries a pulley 52 which is driven by a belt 53 from a pulley 54 that is fixed to a shaft 55 at the opposite end of the machine as best illustrated in Fig. 1.

Carried by the side bar 28 and positioned thereon so as to operate on the paper subsequent to the glue pot is a forming shoe 56 comprising an angle member having a vertical leg 57 attached to the side face of the side bar 28 and having a horizontal flange 58 extending outwardly therefrom to form a longitudinal pressing foot for holding the work in position on the table, as later described, the vertical flange of the angle member being secured to the side bar by headed screws 59 extending through key hole slots 60 whereby the shoe may be readily removed from the machine by lifting the shoe until the enlarged portion 61 of the key hole slots will rise over the heads of the fastening devices.

The forward end of the shoe is curved upwardly 25 as at 62 to permit free entrance of the work pieces thereunder as they are moved into folding relation with the folding shoe 63 that is positioned slightly in advance of the forming shoe to effect folding of the work pieces as they are moved through the machine.

30 The folding shoe 63 includes a flat longitudinal plate 64 having transverse slots 65 for adjustably mounting the plate relatively to the forming shoe. The shoe is secured to the flat top of the plate portion 3 by headed fastening devices 66 having shanks extendable through the slots 65 therein to clamp the plates against the table.

35 Formed along the edge of the folding shoe adjacent the forming shoe is an upwardly off-set and laterally extending folding flange 67 having its forward end lying in the plane of the plate portion of the shoe member 56.

The rear end of the folding flange tapers outwardly and upwardly therefrom to form a gradually rising substantially vertical folding portion 40 70 supporting a horizontal triangular shaped pressing portion 71 adapted to overlie the upper face of the horizontal flange of the forming shoe 56.

50 The forward end of the folding shoe has a downwardly curved finger 72 positioned in an opening 73 in the table top so that as the work pieces are fed along between the belts, the forward edges thereof will ride up the downturned finger so that the edge thereof rides onto the upper face of the folding shoe. As the work pieces are advanced along the shoe, the folding flange gradually turns the edge thereof retractively over the upper face of a work piece or the 55 horizontal flange of the forming shoe depending upon the particular type of work being run through the machine.

When the type of work requires the folding of the work pieces over a card and the folded edge 60 of the work piece to be drawn tightly against the card, the side bar is provided with a rotary wiping disk 74 having its axis positioned at an inclined angle whereby the crowned lower face 75 of the disk engages the turned portion of the 65 work at a single point on its periphery so that when the disk is rotated, the turned portion of the work will be drawn tightly over the card to which it is being attached.

The shaft of the drawing disk is rotatably 70 75 mounted in a bearing 76 extending laterally from

the side of the longitudinal bar 28 and carries a pulley 77 at its upper end that is retained by a wing nut 78 threaded on a projecting end of the shaft and engaging a hub of the pulley 77.

The pulley 77 is rotated from a pulley 79 fixed in driving relation with the pulley 54 through an endless belt running over the respective pulleys and over horizontally positioned pulleys 80 carried on a bracket 81 that is fixed to the side of the table, as shown in Fig. 1.

10 Also secured on the longitudinal side bar 28 is a series of wipers 82, each comprising a flat spring 83 having one end engaging against the top of the table in the path of the work piece and having its other end fixed to an eccentrically mounted hub 84 that is retained in adjusted position on studs 85 projecting laterally from the outer face of the side bar. The hubs thus form cam like elements for variably tensioning the 15 pressing end portions of the wipers to suit the particular work passed through the machine, the eccentric hub being retained in position by set screws 86 threaded therein and engaging against the studs 85.

20 Pivotedly mounted on the longitudinal side bar 28 intermediate the length of the forming shoe are pressing members 87 and 88 having forwardly extending end portions 89 and 90 adapted to engage against the upper face of the work pieces between the folding and forming shoes, as shown 25 in Fig. 3.

25 The shaft carrying the pulleys 54 and 79 is rotatably mounted in a bearing bracket 91 and also forms the driving connection with the end-most pulley 92 of the upper conveyor belt, as 30 shown in Fig. 1.

35 The lower conveyor belt is driven by a shaft 93 that is actuated in timed relation with the shaft 55 through gearing 94 in the housing 95, the gearing in turn being driven from a pulley 96 that is connected through a driving belt 97 with the driving pulley 98 of a motor 99, as shown 40 in Fig. 1.

45 Positioned at the delivery end of the table is a series of off-take belts 100 mounted on rollers 101 and 102 carried by a table extension 103 that has its outer end supported on legs 104 and 105.

50 Assuming that a machine constructed and assembled as described is employed for securing the folded over edge of a sheet to the edge of a card board sheet, the operation is as follows:

55 A stack of the paper sheets is placed upon the work supporting wing 15 and a stack of card boards on the opposite wing or on the unused portion of the shelf. The guide is then adjusted so that it engages one side edge of the card board sheets while the other side moves in alignment with the glue applying wheel and a projecting edge of one of the paper sheets moves in folding 60 relation with the folding shoes. The upper belt is then adjusted relatively to the lower belt to compensate for the thickness of the work by manipulating the hand wheels 43 to raise or lower the belt, as best suited to the particular work at 65 hand.

70 The machine is then started, after which one of the paper sheets "A" is placed upon the slatted feeding table with a side edge thereof in guiding relation with the guide rail.

75 One of the card boards "B" is then placed over the sheet so that one edge thereof also engages the guide rail and leaves an exposed portion of the sheet along its opposite edge which is adapted to be folded over the edge of the card 76

board, as the superimposed card and sheet are advanced through the machine.

As the card board passes under the glue applying wheel, a strip of glue will be applied there-to and when the projecting edge "C" of the sheet "A" rides over the downturned finger on the folded shoe, the edge of the sheet will be lifted thereby onto the plate portion of the shoe. As the work members continue their advance along the table under propelling influence of the belts, the edge "C" of the sheet will move under the folding flange so that it is bent thereby re-tractively over the glued portion of the card board. While the projecting portion of the sheet is being turned over the card board, the card board is retained flat against the table by the depending ends of the pressing members 87 and 88.

After the fold has been formed and the forward ends of the card board and paper sheets emerge from under the shoes, the bent over portion of the sheet is engaged by the rotary disk 14 which draws the folded over portion of the sheet in the direction of the belts so that it is drawn tightly over the edge of the card board. As the work pieces continue their advance, the turned over portion of the sheet will move under the wiping arms 83 which press it into sealing engagement with the glue. The belts continue the advance of the work pieces to move them on the off-take and delivery conveyor 100 at the rear end of the machine.

If it is desired to simply turn back the edge of a sheet of paper, the glue pot may be moved laterally away from the path of travel of the sheet so that the exposed edge thereof is free to ride under the horizontal flange of the forming shoe which retains it in flat condition. In this instance, the projecting edge rides the forming shoe and is turned thereby over the forming shoe as shown in Figs. 9, 10 and 11. As the sheet emerges from under the shoes, it is engaged by the disk to press the fold in tight contact with the body portion of the sheet; however, it may be desirable to lift the disk from contact with the sheet so that the pressing is accomplished solely through the wiper members.

When it is desired to produce double folds in a card board, the side bar 28 is equipped with two sets of folding and forming shoes arranged relatively to each other so that the folds are made in the proper place in the sheets as they are set across the table.

To assist in making the folds, the table may be equipped at its forward end with pairs of scoring disks 106, 107, and 108, 109 that are fixed on a horizontal shaft rotatably mounted in bearings 110 and 111 at the sides of the table and which is driven by a chain and sprocket connection 112 with a suitable driving shaft on the machine such as the shaft for driving the lower conveyor belt.

In order to guide the ends of the work pieces under the scoring rollers, the scoring rollers are provided with a shield 113 having its ends secured to the bearings mounting the score roller shaft as shown in Fig. 12.

In case it is desired to make folds on both edges of the sheet, the table top may be equipped with a second set of folding and forming shoes supported by the other longitudinal bar 27 as shown in Fig. 2 in line with the point at which the fold is to be made on that side of the work piece.

From the foregoing, it is apparent that we have provided a simple, relatively inexpensive machine which is adapted to fold and glue paper

sheets to edges of superimposed card board sheets and by slight change of the machine the folding shoes may be used in folding card board folds and other articles requiring one or more parallel folds.

What we claim and desire to secure by Letters Patent is:

1. In an apparatus of the character described, a support, conveyors for moving superimposed sheets along the support, means for mounting one of the conveyors on the support for movement to and from the other, means for applying glue in spaced relation to an edge of one of the sheets, means carried by the mounting means for pressing the sheets against the support, means bearing on the glued edge of the sheet to prevent curling of said edge, and a folding shoe carried by the support for folding the edge of the other sheet over said glued portion of the first sheet.

2. In an apparatus of the character described, a support, means for moving superimposed sheets along the support, means for applying glue in spaced relation to an edge of one of the sheets, a shoe pressing the sheets against the support, means carried by the support for holding the glued edge of the sheet in sliding engagement with the support, a folding shoe carried by the support for folding the edge of the other sheet over said glued portion, and a wiping disk on the support for drawing the folded edge of said other sheet tightly over the edge of the glued sheet.

3. In an apparatus of the character described, a support, means for moving superimposed sheets along the support, means for applying glue in spaced relation to an edge of one of the sheets, a shoe pressing the sheets against the support, pressing levers carried by the support and having ends engaging the glued portion of said sheet, a folding shoe carried by the support for folding the edge of the other sheet over said glued portion, a wiping disk on the support for drawing the folded edge of said other sheet tightly over the edge of the glued sheet, and a series of wiping elements for yieldingly pressing the folded edge of said other sheet in sealing contact with the glue.

4. In an apparatus of the character described, a support, a pair of upper and lower conveyor belts for moving a sheet along the support, means for adjustably mounting the upper belt on the support for movement to and from the other belt, a forming shoe on said mounting means for engaging one side of the sheet, and a folding shoe carried by the support and having means for folding an edge of the sheet over the forming shoe while the sheet is being advanced by said conveyor belts.

5. In an apparatus of the character described, a support, cooperating conveyors for clampingly engaging the outer sides of superimposed sheets and for moving the sheets along the support, means mounting one of the conveyors to move said conveyor to and from the other conveyor means carried in the path of the sheet for applying glue to a selected portion of one of the sheets, an angle shaped forming shoe carried on said mounting means and having a horizontal flange for engaging the upper sheet, a folding shoe carried by the support and having folding flanges for folding an edge of the other sheet over the glued sheet to form a fold, and means on the support for wiping the folded portion into sealing contact with the glue.

6. In an apparatus of the character described, a support, a fixed conveyor belt on the support,

- spaced longitudinally extending bars adjustably carried on the support, a conveyor belt carried by said bars and cooperating with the fixed belt for moving superimposed sheets along the support, means for applying glue in spaced relation to an edge of one of the sheets, a shoe carried by one of the bars for pressing the sheets against the support, means carried by said support for holding the glued edge of the glued sheet in sliding engagement with the support, a folding shoe carried by the support for folding the edge of the other sheet over said glued portion, and a wiping disk on said bar for drawing the folded edge of the sheet tightly over the edge of the glued sheet.
15. 7. In an apparatus of the character described, a support, a fixed conveyor belt on the support, spaced longitudinally extending bars adjustably carried on the support, a conveyor belt carried by said bars and cooperating with the fixed belt for moving superimposed sheets along the support, means for applying glue in spaced relation to an edge of one of the sheets, a shoe carried by one of the bars for pressing the sheets against the support, means carried by said support for holding the glued edge of the glued sheet in sliding engagement with the support, a folding shoe carried by the support for folding the edge of the other sheet over said glued portion, and a wiping disk on said bar for drawing the folded edge of the sheet tightly over the edge of the glued sheet.
20. 8. In an apparatus of the character described, a table, a shelf at one end of the table, means for moving a sheet from the shelf along the table, means on the table for forming a score in the sheet, a guide strip on the shelf for positioning the sheet relatively to the score forming means, a forming shoe on the table in alignment with the score, and a folding shoe for bending the sheet on the score line over the forming shoe to form a fold in the sheet.
25. 9. In a machine of the character described, a table, a shelf at one end of the table, means carried by the table for forming a plurality of longitudinal score lines in a sheet, a guide strip on the shelf for positioning the sheet relatively to the score forming means, means for moving the sheet along the table to produce said scores, forming shoes on the table aligning with the respective score lines, and folding shoes cooperating with the forming shoes to fold the sheet on said scores.
30. 10. In an apparatus of the character described, a table, a shelf at one end of the table, means for moving sheets from the shelf along the table, means for applying glue in spaced relation to an edge of one of the sheets, a guide strip on the shelf for aligning the sheets relatively to the glue applying means, a shoe pressing the sheet against the table, means carried by the table for holding the glued edge of said sheet in sliding engagement with the table, a folding shoe carried by the table for folding the edge of the other sheet over said glued portion, a wiping disk on the table for drawing the folded edge of said other sheet tightly over the edge of the glued sheet, and a series of wiping elements for pressing the folded edge in sealing contact with the glue.
35. 11. In an apparatus of the character described, a support, a fixed conveyor belt on the support, spaced longitudinally extending bars adjustably carried on the support, a conveyor belt carried by said bars and cooperating with the fixed belt for moving superimposed sheets along the support, means for applying glue in spaced relation to an edge of one of the sheets, a shoe carried by one of the bars for pressing the sheets against the support, means carried by said support for holding the glued edge of the glued sheet in sliding engagement with the support, a folding shoe carried by the support for folding the edge of the other sheet over said glued portion, a wiping disk on said bar for drawing the folded edge of the sheet tightly over the edge of the glued sheet, a forming means carried by the other bar, and a folding means cooperating with said forming means to fold the opposite edge of one of the sheets.
40. 12. In an apparatus of the character described, a support, a fixed conveyor belt on the support, spaced bars adjustably carried on the support, a conveyor belt carried by said bars and cooperating with the fixed conveyor belt for moving superimposed sheets along the support, means for applying glue in spaced relation to an edge of one of the sheets, a shoe carried by one of the bars for pressing the sheets against the support, means for holding the glued edge of the glued sheet in sliding engagement with the support, a folding shoe carried by the support for folding the edge of the other sheet over said glued portion, forming means carried by the other bar, and a folding means cooperating with said forming means to fold the opposite edge of one of the sheets.
45. 13. In an apparatus of the character described, a support, conveyor means on the support, spaced bars adjustably carried on the support, a conveyor means carried by said bars and cooperating with the first conveyor means for moving superimposed sheets along the support, means for applying glue in spaced relation to an edge of one of the sheets, a shoe carried by one of the bars for pressing the sheets against the support, a folding shoe carried by the support for folding the edge of the other sheet over said glued portion, forming means carried by the other bar, and a folding means cooperating with said forming means to fold the opposite edge of one of the sheets.
50. 14. In an apparatus of the character described, a support, conveyor means on the support, spaced bars adjustably carried on the support, a conveyor means carried by said bars and cooperating with the first conveyor means for moving sheets along the support, a shoe carried by one of the bars for pressing the sheets against the support, a folding shoe carried by the support for folding an edge of one of the sheets, forming means carried by the other bar, and a folding means cooperating with said forming means to fold the opposite edge of one of the sheets.
55. 15. In an apparatus of the character described, a support, conveyor belts having runs for clampingly engaging the respective sides of a sheet and for moving the sheet along the support, means mounting one of the conveyor belts for movement to and from the other to vary said clampengagement, means carried by said mounting means and movable in conformity to the conveyor belt for pressing the sheet against the support, and a folding means carried by the support and cooperating with the pressing means for folding an edge of the sheet back upon itself.

DIETRICH DANEKE,
LEO C. WILLIAMS.
